SCRIBING INSTRUMENT

Eugene H. Koenig, Teaneck, N.J., assignor to Keuffel & Esser Company, Hoboken, N.J., a corporation of New Jersey

Filed Oct. 4, 1956, Ser. No. 613,855

2 Claims. (Cl. 33—27)

This invention relates to a scribing instrument of the type used in map making. However, this type of instrument has many other uses and as is known to those skilled in the art can be used in any application where it is desired to make a negative drawing by scribing into an opaque coating provided on a transparent base material.

A scribed drawing can be used directly as a negative for the reproduction of the drawing on photosensitive materials by contact exposure. The present invention is an improvement on the type of scribing instrument which is made up of a heavy body provided with three feet for contacting the surface to be scribed. A spindle carrying the scribing tool is secured to this body and the scribing tool is forced downward against the surface to be scribed by means of a compression spring provided within the spindle.

One object of the present invention is to provide a scribing instrument of the above type with means for drawing small circles of a predetermined radius by merely rotating a shaft carrying the scribing tool.

Another object of the present invention is to provide means on a scribing instrument of the above type which will permit the scribing instrument to be used for drawing straight lines.

These and other objects of the invention and the means for their attainment will be more fully understood after reading the following description taken in conjunction with the accompanying drawing in which:

FIG. I is a view in plan of the new scribing instrument.

FIG. II is a view in elevation partly in section of the new scribing instrument; the sectional part being taken along the horizontal center line of the scribing instrument as shown in FIG. I.

FIG. III is a view of the bottom of the scribing instrument shown in FIGS. I and II with a portion of the magnifier being broken away in order to save space.

FIG. IV is a view in enlarged sectional elevation of the spindle of the new scribing instrument taken along the line IV—IV of FIG. I and looking in the direction of the arrows. The tool holder carried at the lower end of the spindle is not in section.

Referring to the drawings, the body 2 of the scribing instrument is made up of a casting of substantial weight of a material such as brass or the like. For proper functioning of the circle scribing means of the present invention, it is important that the weight of the body be substantially heavier than scribing instruments which have previously been used. The body 2 is provided with three feet 4 which are carried at the lower end of three screws 6 threaded through the casting as shown in FIG. II. Preferably the feet 4 consist of steel balls inserted into recesses provided in the bottom end of the screws 6 and the balls are held in the screws by spinning some of the metal of the screws over the balls. An anti-friction washer such as the washer 7 which may be made of polytetrafluoroethylene may be provided in each of the recesses in the screws 6 above the balls. The body 2 is also provided with a vertical cylindrical hole through the extension 14 of the body to receive the spindle 8. As shown in FIG. IV, the spindle 8 includes a vertical tubular member 10 which is provided with a horizontal shoulder 12 which contacts the upper surface of the body 2. The portion of the vertical tubular member 10 which extends below the shoulder 12 is provided with an outer cylindrical surface

2

which fits the vertical cylindrical hole through the extension 14 of the body 2. A knurled set screw 16 shown in FIG. III is provided to secure the spindle 8 to the body 2.

5 A shaft 18 is mounted in the bore of the vertical tubular member 10 by means of two ball bearings 20 and 22 as shown in FIG. IV. The outer race of the upper ball bearing 20 is mounted in a cap 24 which is free to slide in the vertical direction within the upper enlarged bore 26 of the vertical tubular member 10. A compression spring 28 urges the cap 24 and thereby also the shaft 18 downwardly. Thus a tool 30 carried in the tool holder 32 will be forced against the surface of a scribe material by the pressure of the compression spring 28. The lower end of the shaft 18 is provided with a conical taper 34 terminating in a threaded cylindrical portion of reduced diameter. The lower end of the shaft 18 is also split from line 38 downward. The threaded portion fits a matching thread in the tool holder 32 which is provided 15 with a conical surface which engages the conical portion 34 of the shaft when the tool holder 32 is tightened on the shaft by means of the threads. The engagement of the conical surface compresses the split end of the shaft 18 to hold the tool holder 32 firmly on the shaft. A pin 20 hole 40 is provided in the shaft 18 for use in holding the shaft by inserting a pin therein when the tool holder 32 is tightened thereon.

The tool holder 32 is removable by merely turning it with respect to the shaft 18 to disengage the threaded portion 36 from the tool holder 32. A conventional tool holder may then be attached to the shaft 18 by means of the threaded portion at the end of the shaft and the conical surface 34 or a tool may be inserted directly in the vertical hole in the threaded portion 36A at the end of 35 the shaft 18 and held therein by a suitable chuck engaging the conical surface 34.

As shown in FIG. IV, the tool holder 32 includes a fixed yoke member 41 opening downwardly and a movable block member 42 held in the opening of the yoke member 41 by two screws 43 and 45 which pass through holes in each of the projections of the yoke member 41 and which are threaded into the block member 42. The position of the movable block member 42 in the horizontal direction can be adjusted by manipulating the screws 43 and 45. A scale 47 is provided on the side of yoke member 41 and an index mark 49 is provided on the side of the block member 42. This scale 47 and index mark 49 indicate the horizontal position of the block member 42 and thereby the radius of the tool 30 from the axis of the shaft 18. The tool 30 is held in a vertical hole in the block member 42 and is secured therein by means of the knurled headed set screw 44.

The outer race of the bearing 22 is fixed in the vertical tubular member 10. However, the shaft 18 is free to slide through the inner race of the bearing 22 in order that the shaft 18 will be responsive to the action of the compression spring 28. The upper end of the compression spring 28 is confined by the cap 46 which is threaded on the vertical tubular member 10. The outside surface of the cap is knurled for ease in turning the cap in order to adjust the pressure applied to the tool by means of the compression spring 28.

In order to permit rotation of the shaft 18 so that the 65 tool 30 will scribe a circle of radius determined by the adjustment of the block member 42 a shaft extension 49A passes through the cap 46 and the cap 24 and is secured to the shaft 18 by engaging threads as shown. A knurled wheel 51 is secured to the upper end of the shaft extension 49A by means of a screw 53. A knob 55 is fastened to the knurled wheel 51 by means of a screw 57. The shaft 18 may be turned by means of the wheel 51 or

by using the knob 55 and wheel 51 as a crank means so that the tool 30 will inscribe small circles.

A block 59 which is provided with a lower friction surface as, for example, by cementing thereto a piece of rubber sheet 61 is carried below the body 2 by a second vertical shaft 63 passing through a hole provided near the center of the body 2. A button 65 is secured to the top end of the shaft 63 and a compression spring 66 engages the button 65 and a horizontal shoulder within the hole of the body 2 to lift the friction surface of the block 59 off the surface to be scribed. When it is desired to scribe circles with the scribing instrument, the friction surface 61 is brought into contact with the surface to be scribed by pushing downward on the button 65. This prevents the body 2 from slipping on the feet 4 when scribing the circle since the block 59 is keyed in a rectangular opening at the bottom of the body 2.

A portion of the underside of the body 2 is removed to make room for a straightedge 67 which is held to the body 2 by means of one of the screws 6 and an additional screw 69. The straightedge may be made of any material suitable for straightedges such as steel and the straightedge is provided at the outside edge along the line 71. By sliding the edge 71 along another straightedge the scribing tool will be caused to scribe a straight line. For this purpose, it may be desirable to carry the tool in a conventional tool holder.

A magnifier 56 in the form of a sector of a lens is attached to the vertical tubular member 10 in order to permit close viewing of the tool 30. The magnifier 56 is attached by means of two metal strips 58 and 60 (shown in FIG. I) which are screwed against the radial surfaces of the lens 56 as shown and then bent parallel to each other. The metal strips 58 and 60 are provided with holes to receive the screw 62 which is shown in FIG. II. Another metal strip 64 is bent around the tubular member 10 and is also provided with holes to receive the screw 62. The magnifier 56 may be tilted about the screw 62 as an axis for the best viewing of the tool 30. The magnifier may also be pivoted around the vertical tubular shaft 10 for the same purpose. By tightening a nut provided on the screw 62 sufficient friction can be produced between the metal strips 58 and 60 and the metal strip 64 and between the metal strip 64 and the vertical tubular member 10 so that the magnifier 56 will hold its adjusted position.

Having thus described the invention what is claimed is:

1. A scribing instrument comprising a relatively heavy body provided with three feet for engaging a surface to be scribed, a vertical tubular member carried by said body, a shaft mounted to slide and rotate in said vertical tubular member and projecting below said body, a tool holder carried on the lower end of said shaft including a fixed yoke member opening downwardly and a movable block member held in the opening of said yoke member by two screws threaded into said block member and passing through holes in each of the projections of said yoke member so that the position of said movable block member can be adjusted by means of said screws, a scale provided on said tool holder for indicating the

position of said movable block member with respect to the axis of said shaft, said movable member being provided with means for holding a tool so that the tool may be offset a predetermined amount from the axis of rotation of said shaft, a spring in said vertical tubular member forcing said shaft downward for urging the tool into a surface to be scribed and a handle provided on the upper end of said shaft for rotating said shaft whereby a tool carried by said tool holder can be caused to scribe a small circle of predetermined radius.

2. A scribing instrument comprising a relatively heavy body provided with three feet for engaging a surface to be scribed, a vertical tubular member carried by said body, a shaft mounted to slide and rotate in said vertical tubular member and projecting below said body, a tool holder carried on the lower end of said shaft including a fixed yoke member opening downwardly and a movable block member held in the opening of said yoke member by two screws threaded into said block member and passing through holes in each of the projections of said yoke member so that the position of said movable block member can be adjusted by means of said screws, a scale provided on said tool holder for indicating the position of said movable block member with respect to the axis of said shaft, said movable member being provided with means for holding a tool so that the tool may be offset a predetermined amount from the axis of rotation of said shaft, a spring in said vertical tubular member forcing said shaft downward for urging the tool into a surface to be scribed, a block having a lower friction surface carried below said body by a second vertical shaft passing through said body, a spring urging said second vertical shaft upward to hold said friction surface off of a surface to be scribed, means on said second vertical shaft projecting above the top of said body so that said second vertical shaft can be pushed downward to cause the friction surface to engage a surface to be scribed and thereby prevent the scribing instrument from sliding on the surface to be scribed and a handle provided on the upper end of said first shaft which first shaft is mounted to slide and rotate in said vertical tubular member for rotating said first shaft whereby a tool carried by said tool holder can be caused to scribe a small circle of predetermined radius.
